United States Patent Office

Des. 183,957
Patented Nov. 25, 1958

183,957

NARROW WOVEN FABRIC OR SIMILAR ARTICLE

Leo Beer, Hartsdale, N. Y.

Application February 24, 1958, Serial No. 49,768

Term of patent 7 years

(Cl. D3—32)

Fig. 1

Fig. 2

Figure 1 is a top plan view of a narrow woven fabric showing my new design.

Figure 2 is a side elevational view of Figure 1.

I claim:

The ornamental design for a narrow woven fabric or similar article, as shown.

References Cited in the file of this patent

UNITED STATES PATENTS

D. 66,429	Seel	Jan. 13, 1925
D. 77,330	Shults	Dec. 25, 1928
D. 124,800	Fieger	Jan. 21, 1941
D. 134,234	Wackerman	Oct. 27, 1942